CONTROL FOR TILTABLE MIXING DRUMS

Filed Sept. 30, 1946

UNITED STATES PATENT OFFICE

2,494,118

CONTROL FOR TILTABLE MIXING DRUMS

Bryant Essick, Los Angeles, Calif., assignor to
 Essick Manufacturing Company, Los Angeles,
 Calif., a corporation of California

Application September 30, 1946, Serial No. 700,274

6 Claims. (Cl. 259—176)

1

This invention relates to a control for a tiltable mixing drum and it is a general object of the invention to provide a simple inexpensive and practical control for a tiltable mixing drum such as the drum of a cement or plaster mixer.

Mixers such as are commonly used for mixing cement, plaster, and like materials are commonly constructed with a rotating drum carried in a pivoted yoke and a control is provided to swing or tilt the yoke in order to tilt or vary the angular position of the drum. In the ordinary construction several parts are employed between the handle of the control and the point from which the drum is mounted, and these parts are joined or coupled through ordinary mechanical connections such as keys, pins, nuts, etc.

Machinery of this character is not precision made and, in practice, it receives very hard usage, with the result that the joints or connections above mentioned soon develop play or looseness which is highly undesirable. For example, when play or looseness develops in the control above referred to, or between the control and the drum, the mechanism becomes hazardous since tilting of the drum may change the center of gravity of the loaded drum and as the center of gravity changes the play or looseness is shifted from one direction to the other, allowing the drum to fall, or quickly move an amount allowed by the total play or looseness. Such falling or quick movement of the drum may cause spilling of the contents therefrom, which may, under certain circumstances, be dangerous to workmen and which defeats the purpose of the control in that it makes it impossible for the operator to accurately control tilting of the drum.

It is an object of this invention to provide a control for a machine of the character mentioned which involves a single joint or connection between the point at which the drum is mounted and the handle of the control. The single joint or connection provided in the structure that I have provided is a working joint or connection and is the only possible point at which play or looseness can occur. By providing a mechanism involving a single point of possible play or looseness I minimize the difficulties hereinabove outlined and provide a machine that is safe and dependable in operation. A further object of the present invention is to provide a control of the general character referred to in which the single joint or connection where relative movement occurs is a gear connection where a pinion meshes with a gear and being a gear connection it is not subject to excessive wear or to becoming loose.

2

in a manner to create appreciable looseness between the handle of the control and the drum.

It is a further object of the present invention to provide a control of the general character referred to which involves a geared drive or connection in which one element or gear is integrally joined to the yoke on which the drum is mounted, while the other is integrally joined to the handle of the control.

The various objects and features of my invention will be fully understood from the following detailed description of a typical preferred form and application of the invention, throughout which description reference is made to the accompanying drawings, in which:

Fig. 1 is a side elevation of a typical mixer embodying the present invention; Fig. 2 is an enlarged view of parts of the control, being a view taken as indicated by line 2—2 on Fig. 1, and Fig. 3 is an enlarged detailed sectional view taken substantially as indicated by line 3—3 on Fig. 2.

The control that I have provided is applicable to mixers generally. However, since it is particularly useful as applied to or incorporated in mixers such as are employed to mix cement or plaster, I have in the drawings shown it applied to a typical cement mixer. The particular machine illustrated involves, generally, a frame A, a yoke B, bearings C carried by the frame and supporting the yoke, a mixing drum D, a pivotal mounting E for the mixing drum by which it is pivotally supported from the yoke; drive means F for the drum; and control means G for the drum controlling tilting of the drum through the yoke B.

The frame A that I have illustrated is a rigid, fabricated structure normally held in the desired position by supporting wheels W and a leg 10. The bed or base 11 of the frame extends substantially horizontally and is supported from the wheels through springs 12 and by the leg 10 through a direct connection with the leg. The frame is characterized by spaced uprights 14 which carry the bearings C that in turn support the yoke B. A rearward extension 11a of the base forms a support or carrier for a housing 15 provided around the power means or engine of the drive means F.

The yoke B is a rigid element involving a center section or body 16 and spaced parallel sides or arms 17. In accordance with my construction the yoke includes trunnions 18 at the outer ends of the arms 17. The trunnions 18 are integrally joined to or formed with the arms 17 and are arranged so that they are co-axial and so that they project laterally from the outer

sides of the arms at the outer end portions thereof.

The bearings C provided to support the yoke from the frame preferably involve split bearings one on the upper end of each support 14 of the frame and each embodying a lower or seat section 20 rigidly joined with or integrally formed on the upper end of the frame support and a removable top or cap section 21. The bearings C are carried by the supports 14 so that they are spaced apart to accommodate the yoke, as shown in the drawings. The arms of the yoke are confined between the bearings C while the trunnions 18 of the yoke are rotatably supported in the bearings.

The mixing drum D that I have illustrated is of the form or type commonly employed in cement mixers and has a round body 25 enclosed at its lower end by a curved bottom 26 and provided at its upper end with a somewhat contracted or conical neck portion 21, the neck portion being open allowing material to be filled into or discharged from the drum, as desired.

The mounting means E for the drum D is a pivotal mounting by which the drum is directly supported from or in the yoke. The mounting means E serves to pivotally connect the bottom 26 of the drum to the body 16 of the yoke so that the drum is free to turn relative to the yoke on an axis which is transverse of the body of the yoke and which intersects the axis of the trunnions 18.

The drive means F for the drum D includes a suitable source of power or prime mover such as an engine located in the housing 15. I have not shown the details of the engine in the housing since my present invention is in no way concerned with this detail. The drive to the drum involves a pinion 28 driven by the engine or prime mover which pinion meshes with a ring gear 29 fixed to the exterior of the body 25 of the drum B.

The control G that I have provided governs the tilt of the drum D or forms a means by which the yoke B is tilttable about the axis of the trunnions 18, it being apparent that when the yoke B is swung about the trunnions the drum which is carried by the yoke is tilted and can be varied between an upright position such as is shown in Fig. 1 and an angular position where the top of the drum is lowered either to facilitate filling of material into the drum or to allow material to discharge from the drum. The control means G may be applied to or connected with either of the trunnions of the yoke, it being preferred, ordinarily, to locate the control means at the forward end of the machine so that it is remote from the drive which is preferably located at the rear end of the machine.

In the form illustrated the control means G includes, generally, a hub 30 rotatably supported on a bearing pin 31 projecting from an upright 14 of the frame A, a rim 32 is supported from the hub 30 by spokes 33 and forming a handle to be gripped by the operator, a gear 34 fixed to the outer or projecting end of the trunnion 18 supported in the bearing C carried by the support 14 which carries the bearing pin 31, teeth 35 on the hub 30 forming a pinion meshing with the gear 34 and a manually controlled lock means 36.

The bearing pin 31 which carries the hub 30 is supported by the support 14 of the frame to project from the outer or forward side thereof,

and in the case illustrated it has a bearing part 40 on which the hub operates and a reduced end part 42 which extends through the support 14 and carries a mounting nut 43. The hub 30 is freely turnable or is rotatably supported on the portion 40 of the bearing pin and is retained thereon by a suitable retainer 45.

The hub 30 may have a plain outer end portion 46 which carries the spokes 33 and thus becomes, in effect, the hub of a wheel which includes the spokes and the rim 32. In accordance with my invention the inner ends of the spokes are integrally joined to the outer portion 46 of the hub as by welding 60 while the outer ends 16 of the spokes are integrally joined to the rim 32 as by welding 61. Through this construction the spokes and rim become an integral part of the hub or of the unit which includes the hub and the teeth 35 which mesh with the gear 34. The inner end portion 47 of the hub has the gear teeth 35 milled or otherwise formed in it, the teeth being formed completely around this part of the hub so that the inner end portion of the hub is a pinion that meshes with the gear 34.

25 The gear 34 is not merely keyed or bolted to the trunnion 18 through an ordinary connection such as is ordinarily employed in such a situation, but rather it is integrally joined to the trunnion so that the gear 34 is an integral part of 30 the yoke B. In practice I have found it desirable to form the gear 34 separate from the yoke in which case it may be in the nature of a plate integrally joined to the outer end of the trunnion 18, as by welding 49. By providing a split bearing C such as I have described above I am able to initially establish the gear 34 as an integral unit with the yoke B and in assembling the machine the yoke, with the gear as a part thereof, is placed in the seat 20 of the bearing whereupon 40 the cap of the bearing is arranged in place.

To facilitate ease in operation I prefer to make the gear 34 of substantial diameter relative to the pinion on the inner end of the hub 30 with the result that the operator engaging the rim 32 has a substantial mechanical advantage over the yoke and is able to turn or tilt it with little effort.

45 The lock means 36 of the control preferably includes a simple lock dog 50 on a pivot pin 51 supported by a bracket 52 projecting upwardly from the frame or from the cap of the bearing C supported by the frame. The dog 50 is preferably arranged so that it is normally held in engagement with the gear 34 by gravity and it is provided with a handle 55 which projects forward so that it can be conveniently operated, enabling the operator to release the lock means when he wishes to operate the control to tilt the drum.

Under normal conditions the lock 36 is engaged with the gear 34 so that the yoke B is held against turning or tilting movement. When the operator desires to turn or tilt the yoke B and consequently the drum D he disengages the lock means 36 and operates the handle or rim 32 in the desired direction. Turning of the rim 32 rotates the pinion portion of the hub which is integral with the rim 32 being integrally joined thereto by the spokes 33. Rotation of the pinion portion of the hub causes rotation of the gear 34 through engagement of the hub with the teeth of the gear. The gear 34 being integrally joined to the trunnion 18 turns the trunnion and consequently the entire yoke B. It is to be observed that through the construction that I have provided the structure is solid or integral from the

point of the yoke where the drum is rotatably supported to the point where the teeth of the gear 34 mesh with the teeth of the hub 30. Furthermore, it will be apparent that the structure is solid or integral from the teeth 35 through the hub 30, spokes 33 and the rim 32. The result of this construction is that there is only one possible point for looseness or play to develop and this is in the working connection established between the pinion of the hub and the gear 34.

As a result of the construction that I have provided the drum is not only easy to tilt or operate as desired, but it is free of undesirable play or looseness and such play or looseness can never develop even though the machine is subjected to strenuous use, since there are no mechanical joints or connections of a character that can possibly work loose or develop freedom due to wear or strain.

Having described only a typical preferred form and application of my invention, I do not wish to be limited or restricted to the specific details herein set forth, but wish to reserve to myself any variations or modifications that may appear to those skilled in the art and fall within the scope of the following claims.

Having described my invention, I claim:

1. A mixer including, a frame, a yoke pivotally supported by the frame, a drum rotatably supported in the yoke, and a control for the yoke including, a handle, a gear element integral with the handle, a gear member integral with the yoke and meshed with the first mentioned gear member, and a lock member engageable with the teeth of one of said gear elements, the lock member being pivotally mounted on the frame.

2. A mixer including a frame carrying spaced coaxial bearings, a yoke with integral coaxial trunnions projecting from the sides of the yoke and supported in the bearings, a gear integral with the outer end of one of the trunnions and concentric therewith, a bearing pin rigidly carried by the frame and projecting therefrom, a hub rotatably carried on the pin and having teeth meshing with the gear, an annular handle, spokes integral with the hub and with the handle, and a lock dog pivotally mounted on the frame to engage the teeth of the gear.

3. A mixer including, a frame, a yoke pivotally supported by the frame, a drum rotatably supported in the yoke, and a control for the yoke including, a handle, a gear element operatively connected with the handle, a member operatively connected with the yoke and meshed with the first mentioned gear element, and a gravity actuated lock member carried by the frame and engageable with the teeth of the gear element.

4. A mixer including, a rigid frame with spaced aligned bearings, a yoke with trunnions pivotally supported by the bearings of the frame, a drum rotatably supported in the yoke, and a control for the yoke including, a pin rigid with and projecting outward from the frame, an integral unit including a handle and a gear element rotatably supported on the pin, a gear element larger than the first mentioned gear element and integrally connected with a trunnion of the yoke and meshed with the first mentioned gear element, and a lock member pivoted to the frame and engageable with the teeth of the larger gear element.

5. A mixer including, a frame, a yoke pivotally supported by the frame on a horizontal axis, a drum rotatably supported in the yoke, and a control for the yoke including, a handle, a gear element integral with the handle, a pin rigid with the frame projecting outward therefrom and rotatably supporting said gear element, a gear element larger than the first mentioned gear element and integral with the yoke and meshed with the first mentioned gear element, a bracket rigid with the frame and projecting from the frame to a point adjacent the periphery of the larger gear element, and a lock member pivotally carried by the bracket and engageable with the teeth of the larger gear element.

6. A mixer including, a frame carrying spaced coaxial bearings, a yoke with trunnions carried in the bearings, a drum rotatably supported in the yoke, and a control for the yoke including a gear fixed on one trunnion, a hand wheel rotatably mounted on the frame, a gear fixed to the wheel and meshing with the first mentioned gear, a bracket projecting up from the bearing carrying said trunnion, and a lock member pivotally carried by the bracket and normally held by gravity in engagement with teeth of the first mentioned gear.

BRYANT ESSICK.
